(57) **CLAIM**

The ornamental design for an aquarium stand, as shown and described.

DESCRIPTION

FIG. 1 is a front right perspective view of an aquarium stand in accordance with the present design;

FIG. 2 is a front view of the aquarium stand shown in FIG. 1; FIG. 3 is a back view of the aquarium stand shown in FIG. 1; FIG. 4 is a top view of the aquarium stand shown in FIG. 1; FIG. 5 is a bottom view of the aquarium stand shown in FIG. 1;

FIG. 6 is a left side view of the aquarium stand shown in FIG. 1; and,

FIG. 7 is a right side view of the aquarium stand shown in FIG. 1.

The broken line showing of an aquarium stand is for the purpose of illustrating environmental structure and forms no part of the claimed design.
